Atty.

UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,352,568.

Specification of Letters Patent. Patented Sept. 14, 1920.

Application filed May 8, 1918. Serial No. 233,259.

To all whom it may concern:

Be it known that I, CHARLES WHITE, a citizen of the United States, residing at East Orange, in the county of Essex, State of New Jersey, have invented certain new and useful Improvements in Telephone Systems, of which the following is a full, clear, concise, and exact description.

This invention relates to telephone systems and more particularly to systems of the central energy type in which a distinctive tone is employed to give an audible signal in the operator's receiver on testing a telephone line to indicate the idle or busy condition of that line.

In telephone systems in which polystation lines form a part, it often occurs that one subscriber on a particular polystation line desires to be connected with another subscriber on the same polystation line. Inasmuch as the jacks of all the stations on that line would test busy when the answering operator inserts the answering end of a cord circuit into the jack of the calling party, it has been found necessary to give a different signal to distinguish between this condition and the condition existing when a call is extended to another busy line. Testing arrangements of this character are known in the art as reverting busy tests. While various reverting busy test arrangements have been suggested, the range of permissible variations from ideal conditions has been somewhat limited, requiring close adjustment and careful supervision of the apparatus involved and the object of the present invention is to provide an improved reverting busy test system of increased efficiency capable of operation over a wide range of operating conditions.

In accordance with a feature of the invention, there is provided a cord circuit of the usual type with which there is associated a busy test relay for controlling the connection of a source of tone supply with a test conductor of the cord circuit and in addition there is provided a resistance coil which is adapted to be connected in parallel relation with the test conductor of the cord circuit upon the actuation of the listening key to effect the operation of the busy test relay.

In the accompanying drawing, a telephone system is diagrammatically shown which illustrates one embodiment of the invention.

For the purpose of illustrating the invention, assume that subscriber A desires to converse with subscriber B whose station is on the same line as that of subscriber A. A would initiate the call by removing the receiver at his station from its switchhook, thereby causing the operation of line relay 4 which in turn completes the circuit for line lamp 5. The operator, upon observing the lighted condition of line lamp 5, inserts the answering plug 6 of the cord circuit C into jack 7, whereupon cutoff relay 8 is operated over a circuit extending from battery through the supervisory lamp 10, normal contact of relay 9, sleeve contacts of the plug 6 and the jack 7, and winding of cutoff relay 8 to ground. The operation of this relay causes the release of line relay 4 which in turn causes the effacement of line lamp 5. Supervisory relay 9 is also operated an instant later over a circuit extending from battery through winding 32 of the repeating coil 11, winding of supervisory relay 9, ring contacts of the plug 6 and the jack 7, substitution apparatus of station A, tip contacts of the jack 7 and plug 6, and winding 33 of repeating coil 11 to ground. The operation of relay 9 opens at its normal contact the low resistance path extending in parallel about resistance 21 and connects at its alternate contact, a battery supply so poled as to oppose the battery associated with the supervisory lamp 10. The lamp 10 is thereby effaced on the operation of relay 9 and while the resistance in the circuit previously traced for the cutoff relay 8 is increased due to the opening of the parallel path about resistance 21, the two batteries just mentioned act in a parallel aiding relation as regards current passing through the resistance 21 and thus supply sufficient current to relay 8 to maintain it in actuated position.

The operator would now actuate listening key 12 which connects the operator's telephone set 13 to the talking strands of the cord circuit, thereby permitting the operator to ascertain the number of the called-for party. The actuation of key 12 also prepares a circuit for the tone supply 14, which is adapted to be connected to the sleeve conductor of plug 6 through contact 15 of this key. The resistance 20 is at the same time connected in parallel relation with the sleeve conductor of the cord circuit and is provided for the purpose of reducing the ef-

fective resistance therein, as will appear more clearly from the following description. A circuit for a busy test relay 16, preferably common to a plurality of cord 5 circuits, is also established through contact 17 of listening key 12 on actuation thereof.

On ascertaining that subscriber A desires to be connected with subscriber B, the operator would touch the tip of the calling plug 10 18 to the sleeve contact of jack 19 which is individual to station B, in order to determine whether or not the line is idle or busy. In the case of polystation lines, each subscriber has an individual answering jack, 15 the numbers of which are in many cases radically different from the numbers of other subscribers on the same line, so that the number called does not in itself indicate to the operator whether the called-for party 20 is on the same line as that of the calling party or not. In order to determine this fact, it is necessary to test the line as above indicated. When the connection has been completed between the tip of plug 18 and 25 the sleeve of jack 19, relay 16 is operated over a circuit extending from battery through the alternate contact of supervisory relay 9, resistance 21, sleeve contacts of the plug 6, jacks 7 and 19, tip contact of plug 18, 30 contact 17 of key 12, and the winding of busy test relay 16 to ground. The operation of relay 16 thereby connects a source of tone supply 14 with the test conductor, producing a click in the operator's receiver, followed by a tone which indicates whether or 35 not the called-for party is on the same line as the calling party. In systems as herein represented, the operation of relay 16 is assured as the shunting effect of winding 40 31 of repeating coil 11 which is connected in parallel relation with the winding of busy test relay 16 is thereby minimized. The resistance of winding 31 of repeating coil 11 is preferably much lower than that of 45 the winding of relay 16, therefore, the current flow through the latter is in many cases not of a sufficient strength to cause its operation since a large amount of the total current flows through winding 31 of repeating coil 50 11. Resistance 20 which is connected in parallel with resistance 21 through contact 15 of the listening key thereby reduces the effective resistance of the sleeve conductor, so that the current strength is increased to 55 such an amount that the busy test relay 16 receives an amount of current sufficient to effect its operation upon the completion of the above connection.

The circuit for such tone may be traced 60 from the source 14 through the contact of busy test relay 16, contact 15 of listening key 12, sleeve conductor of the cord circuit C, sleeve contacts of the plug 6, jacks 7 and 19, tip contact of plug 18, contact 17 of key 12, induction coil 22 of the operator's

telephone set 13, receiver 23, condenser 24, contact 25 of key 12, winding of calling supervisory relay 26, winding 34 of repeating coil 11, and battery to ground. The operator thereupon receives a definite tone 70 signal in her receiver distinctly different from the click of the usual busy test signal and is thereby advised that the called-for party is on the same line as the calling party. Plug 18 would then be inserted into 75 jack 19 which causes the operation of supervisory relay 26 to effect the effacement of supervisory lamp 27 as before described, and the release of the busy test relay 16 which in turn disconnects the tone supply 80 14 from the sleeve conductor of the cord circuit. Party B would then be signaled in any desired manner.

To illustrate the difference in character of the signals received by an operator in testing a busy line other than that of the calling subscriber, assume that subscriber A desires to converse with party D, who is on another telephone line. In this case, the operator would engage the tip contact of the calling plug 18 with the sleeve contact of the jack 28 belonging to the line of party D. The usual busy test click will be produced in the operator's receiver if the line tested is busy upon the engagement of the tip contact of the plug 18 to the sleeve contact of jack 28, and relay 16 may also be operated, but no tone will be produced in the operator's receiver, due to the fact that the answering end of the cord circuit is engaged by the jack of another line. However, if the line tested is idle, there will be no click produced in the operator's receiver. The plug 18 may then be inserted into jack 28, causing the operation of cutoff relay 29 105 which opens the circuit for line relay 30. Supervisory lamp 27 is also illuminated upon the insertion of plug 18 into jack 28. The party D would then be signaled in any desired manner. The called-for subscriber 110 upon the removal of the receiver from the switchhook causes the operation of supervisory relay 26 over a circuit similar to that of relay 9, the operation of which arranges a shunt about the supervisory lamp 27 which 115 causes the effacement of the same.

When the conversation has been completed, and the subscribers again restore their receivers to the switchhooks, supervisory relays 9 and 26 are thereupon released, which opens the circuit of the opposing batteries, thereby causing the supervisory lamps 10 and 27 to be illuminated. The operator, upon observing the lighted condition of these lamps, can then remove 120 the plugs from the respective jacks, which restore all apparatus to normal.

What is claimed is:

1. A telephone exchange system comprising a telephone line terminating in a plu- 130

rality of jacks, a cord circuit having a test conductor, a resistance coil, a test relay, and means serving when actuated to connect said resistance in parallel relation with the test conductor to thereby effect the operation of said test relay.

2. A telephone exchange system comprising a telephone line terminating in a plurality of jacks, a three-conductor cord circuit, a listening key, a test relay, and a resistance coil common to a plurality of cord circuits, said resistance coil being connected in parallel relation with the third conductor of said cord circuit upon the actuation of 15 said key to effect the operation of said relay.

3. A telephone exchange system comprising a telephone line terminating in a plurality of jacks, a three-conductor cord circuit, the answering end of which is adapted 20 to be associated with one of said jacks, a busy test relay, an operator's telephone set including a receiver, a resistance coil, and a listening key for connecting said operator's telephone set with the talking conductors of said cord circuit and to connect said 25 resistance coil in parallel relation with the third conductor of said cord circuit, said busy test relay being operated upon the engagement of the calling end of said cord circuit with the test thimble of another jack 30 of the same line to produce an audible tone in the operator's receiver.

4. A telephone exchange system comprising a telephone line terminating in a plurality of jacks, a three-conductor cord circuit,

the third conductor of said cord circuit serving as a test conductor therefor and being adapted to be connected with the test terminal of one of the jacks to determine the idle or busy condition of the line, a busy 40 test relay, a listening key, and a resistance coil connected in parallel relation with the test conductor upon the actuation of said key to effect the operation of said relay.

5. A telephone exchange system comprising a telephone line terminating in a plurality of jacks, a plurality of cord circuits having a test conductor adapted to be connected with a test thimble of a jack to determine the idle or busy condition of the 50 line, an operator's telephone set, a busy test relay, a resistance coil common to said cord circuits, and means for connecting the operator's telephone set with the talking conductors of said cord circuit and to connect said 55 resistance coil in parallel relation with the test conductor of said cord circuit to effect the operation of said relay.

6. A telephone exchange system comprising a telephone line terminating in a plurality of jacks, a three-conductor cord circuit, a test relay, a resistance coil common to a plurality of cord circuits, and a listening key adapted when actuated to connect said resistance coil in parallel relation with 60 a conductor of said cord circuit to thereby assure the operation of said relay.

In witness whereof, I hereunto subscribe my name this 2nd day of May A. D., 1918.

CHARLES WHITE.
